By his Attorney *J. M. R. Gerhard*

UNITED STATES PATENT OFFICE.

SIMON B. MINNICH, OF LANDISVILLE, PENNSYLVANIA.

PRESS.

SPECIFICATION forming part of Letters Patent No. 366,339, dated July 12, 1887.

Application filed April 22, 1887. Serial No. 235,737. (No model.)

To all whom it may concern:

Be it known that I, SIMON B. MINNICH, a citizen of the United States, residing at Landisville, in the county of Lancaster and State 5 of Pennsylvania, have invented certain Improvements in Presses, of which the following is a specification.

This invention relates to baling-presses, and is an improvement upon a tobacco-press for 10 to which Letters Patent No. 173,736, dated February 22, 1876, were granted me; and it consists in the construction and combination of the various parts, as hereinafter fully described and claimed, and as illustrated in the accompanying drawings, which form a part of this 15 specification, in which—

Figure 1 is a top view of my press; Fig. 2, a side view, and Fig. 3 an end view. Fig. 4 is an enlarged side view of the means of applying power to the shaft. Fig. 5 is an enlarged side view of the clamp at the ends; Fig. 6, an enlarged top view of the same; and Fig. 7, a vertical cross-section through one of the sides on the line $x-x$, showing the vertical ratchet.

Similar letters refer to similar parts throughout the several views.

S represents the press-beam, formed of a piece of metal set on edge, and having somewhat the shape of an S, one lobe or curve, s, resting 30 upon one side of the longitudinal piece I of the follower, and the other, s', upon the other side, the intersection of the curves being at the center of the plank I, and the ends of the beam extending over the center of the ends of 35 the plank and out of the narrow space c between the sections C of the ends of the box. The beam is strengthened by a truss, composed of the post T, at the center, and the tension-rod t, secured to the beam near the ends, and supported in the middle by said post. The ends 40 of the beam are turned downward and furnished with an opening, o, by which the windlass-chains H are attached. Turning down the ends of the beam prevents any tendency it 45 might otherwise have to turn sidewise. By the use of this beam the sections of the end pieces can be brought closer together, having the space which divides them of equal width from top to bottom, and the pressure upon the 50 follower is distributed over a greater surface,

and is at all times exerted in a direct vertical direction.

The catches by which I connect the sides A of the press while the contents are being pressed are composed of two sections, one bolted to 55 each of the sections C of each end, and having the outer end of each section embracing the corner of the press by means of the ears p' g', to give a better hold to the catches. The section Q is jointed, the outer end, q, being bolted 60 fast, and having jaws j, in which the end J is pivoted by the screw-bolt j'. The free end of the part J is supplied with a hook, h, for engaging with the other section, P, of the catch. The section P is also bolted to the press and 65 supplied with jaws at its inner end. At the mouth of these jaws a curved lever, L, is pivoted on the screw-bolt b. The lever when in its normal position curves downward from the eye through the jaws, as at l, and then upward 70 through the rear of the opening between said jaws, terminating in a rearwardly-extending handle, l'. The hook h embraces the eye p of the lever L, which is cam-shaped on its inner side, with its end resting upon the bearing-lip 75 p', projecting inward from the lever just below the eye. When the press is packed, these catches are subjected to great pressure; but notwithstanding this the application of a slight force to the lever, with the action of the cam- 80 shaped eye, readily disconnects the parts of the catch. As this press is now constructed, the corners are secured by angle-irons, the arms thereof extending well over the side and end pieces, and being bolted thereto to prevent any spreading of those parts under the 85 severe strain to which they are subjected. I also make use of other means for turning the shaft.

In addition to the ratchet M, used in my invention previously mentioned, to which the detached lever is applied, I use a second ratchet, R, with a pawl, V, on the shaft K, placing it several inches out from the face of the press, and near and about on a line with 90 it I have a pin, G, projecting. The detachable lever D is provided with a link, E, hinged to one side near the lower end, adapted to be folded up against the side of the lever D when not in use, and there held by a catch, F. In 95 100

use, the concavities of the plates *d* on the lower end of the lever *D* are engaged with the pin *G*, the link is connected with one of the teeth of the ratchet, and the power applied to the 5 lever. In this way much increase of power is obtained over the old means employed.

The ends of the beam *I* of the follower are strengthened by metal bands *i*, which project above the upper face of said beam, where they 10 are supplied with centrally-located grooves *k*, which receive the lower edges of the beam *S*, and preserve it from lateral motion.

Upon the inner face of each side wall there are secured two or three vertical racks, *U*, with 15 their teeth turned downward, as shown in Fig.

7. These racks tend to prevent the uprising of hay or similar articles being baled, which have been pressed down, when the follower is raised to permit the press to be replenished.

20 Having thus described my invention, what I claim as new, and desire to secure by Letters Patent, is—

1. The combination, with the follower *I* and the chains *H* and their operating mechanism, 25 of the **S**-shaped press-beam *S*, substantially as and for the purpose set forth.

2. The combination, with the chains *H* and their operative mechanism, of the follower-beam *I*, having centrally-located slots at the ends, adapted to receive the press-beam *S*, and 30 said press-beam, substantially as and for the purpose specified.

3. The combination, in a press, of the catches secured to the end sections of the press, one section, *Q*, of the catch having a hook, *h*, 35 adapted to engage with the other section, *P*, and the section *P*, provided with a lever, whereby the two sections are disconnected, substantially as and for the purpose specified.

4. The combination, in a press, of the catches 40 secured to the end sections of the press, one section, *Q*, of the catch having a hook, *h*, adapted to engage with the other section, *P*, and the section *P*, provided with a cam-lever, *L*, whereby the two sections are disconnected, 45 substantially as and for the purpose specified.

SIMON B. MINNICH.
